UNITED STATES PATENT OFFICE.

STERLING H. CAMPBELL, OF ST. LOUIS, MISSOURI, ASSIGNOR TO RAILWAY DEVICES COMPANY, OF ST. LOUIS, MISSOURI, A CORPORATION OF MISSOURI.

ANGLE-COCK HOLDER.

1,212,184.

Specification of Letters Patent.

Patented Jan. 16, 1917.

Application filed November 1, 1916. Serial No. 128,870.

To all whom it may concern:

Be it known that I, STERLING H. CAMPBELL, a citizen of the United States of America, residing at the city of St. Louis, State 5 of Missouri, United States of America, have invented a certain new and useful Angle-Cock Holder, of which the following is such a full, clear, and exact description as will enable any one skilled in the art to which it 10 appertains to make and use the same, reference being had to the accompanying drawings, forming part of this specification.

My invention relates to an angle cock holder, and more particularly to one which 15 can be adjusted in the direction of the length of the train pipe to accommodate pipes of varying lengths.

In the accompanying drawings, which 20 illustrate two forms of angle cock holder made in accordance with my invention, Figure 1 is a side view, the angle cock being shown in dotted lines; Fig. 2 is a front view of the part shown in Fig. 1, the angle cock and train pipe being omitted; Fig. 3 is a 25 view similar to view of Fig. 1, but showing a modification; Fig. 4 is a front view of the parts shown in Fig. 3, the holder and a U-bolt being detached; Fig. 5 is a side view of the holder shown in Figs. 3 and 4; Fig. 6 is 30 a detailed view of the beveled washer used in connection with the modification shown in Fig. 3.

Like marks of reference refer to similar 35 parts in the several views of the drawings. 10 represents a portion of a railway car, to which the angle cock holder is adapted to be attached.

11 represents a train pipe, and 12 the angle cock. In the forms shown in Figs. 1 and 40 2 of the drawings the train pipe 11 extends some distance below the part 10 of the car to which the holder is to be attached. In this construction a plate 14 is secured to the car 10 by means of rivets or bolts 15, passing 45 through holes 16 near the upper edge of the said plate 14. Formed in the plate 14 is an opening 17, corresponding in shape to the body of the angle cock holder 18, but somewhat larger. The angle cock holder 18 is 50 in general form somewhat similar to that shown in my prior Patent No. 1,031,419 of July 2nd, 1912, the angle cock being held in position in the holder by means of a cotter pin 19. The holder, however, differs from

that shown in my said prior patent in being 55 provided with a number of recesses or grooves 20, formed in the lower part thereof and arranged in the direction of its length, so that the grooves are adapted to engage with the lower edge of the opening 17, and thus positively adjust the holder in the direction of the length of the train pipe 11, so as to enable the holder to be used with train pipes of varying lengths. In order to prevent the recesses 20 from becoming 60 disengaged from the lower edge of the holder 17, I provide a member 21, which is pivoted to the plate 14 just above the opening 17, by means of a rivet or bolt 22, which rivet or bolt allows the said member 21 to 65 be turned upwardly to permit the insertion or removal of the holder 18. It can also be turned downwardly to prevent the said holder from being raised out of engagement with the lower edge of the opening 17, as 70 shown in the drawings.

In Figs. 3 to 6 I have shown a modified form of holder for use where the train pipe 11 passes directly below the part 10 of the car to which the holder is to be attached. 80 In this construction I use a two-part holder 24, which is somewhat similar to the holder shown and described in my prior Patent No. 1,156,463 of October 12, 1915. This holder, however, is provided at its lower edge with 85 a number of grooves 20, as has hereinbefore been described in connection with the holder shown in Figs. 1 and 2. These grooves 20 are adapted to engage with a U-bolt 25, passing around said holder and through openings formed in the flange of the part 10. The upwardly extending ends of the bolt 25 are engaged by a beveled washer 26, shown in detail in Fig. 6, the use of which washer gives a surface at right angles to the direction of the length of the bolt for the engagement of nuts 27, by means of which the parts are held together. It will be evident 90 that by loosening the nuts 27 sufficiently to allow the U-bolt to move down out of engagement with the notches or recesses 20 the holder 24 can be adjusted longitudinally to suit varying lengths of train pipe, but that after the bolt has been brought into engagement with the notches and tightened, 105 the parts will be firmly held in their proper position.

Having fully described my invention,

what I claim as new and desire to secure by Letters Patent of the United States is:

1. In an angle cock holder, the combination with a receiver adapted to engage the head of an angle cock and prevent its rotation, of means adapted to engage the said receiver at different points in the direction of its length and positively securing it to a railway car.
- 10 2. In an angle cock holder, the combination with a receiver adapted to engage the head of an angle cock and prevent its rotation, of a plurality of recesses formed in said receiver in the direction of its length, and means adapted to engage with one of said recesses and thus positively secure said receiver to a railway car.
- 15 3. In an angle cock holder, the combination with a receiver adapted to engage the head of an angle cock and prevent its rotation, said receiver having recesses formed in the direction of its length, of a plate provided with an opening for the passage of said receiver, the edge of said opening being adapted to engage with said recesses, and means for holding said edge in engagement with said recesses.
- 20 4. In an angle cock holder, the combi-

nation with a receiver adapted to engage the body of the angle cock and prevent its rotation, said receiver being provided with recesses arranged in a direction of its length, of a plate provided with an opening for the passage of said receiver, the edge of said opening being adapted to engage with said recesses, and pivotally mounted means for holding said edge in engagement with said recesses.

35 5. In an angle cock holder, the combination with a receiver adapted to engage the head of an angle cock and prevent its rotation, of a removable member carried by said receiver and adapted to engage with the front face of the angle cock head and prevent the removal of the angle cock from the receiver, the body of said receiver being provided with a plurality of recesses, of a plate provided with an opening for the passage of the body of said receiver, the edge of said opening being adapted to engage with one of said recesses, and a member carried by said plate for holding said edge in engagement with said recesses.

40 45 In testimony whereof, I have hereunto set my hand and affixed my seal.

STERLING H. CAMPBELL. [L. S.]
